WINDOW VENTILATOR

Lewis O. Stewart, Detroit, Mich.

Application July 13, 1931, Serial No. 550,486

7 Claims. (Cl. 98—121)

The present invention pertains to a novel ventilator of the adjustable type adapted to be inserted in windows and the like.

The primary object of the present invention is to provide a ventilator formed of a plurality of panels that slide lengthwise relative to each other in a manner whereby the ventilator may be adjusted in length to accommodate itself to windows of varying widths. Each of the plurality of panels are identical in construction and size which avoids the expense of a machine set up to stamp the parts of different sizes so that one member may slide within another as is necessary in telescoping ventilators. The panels are formed with series of overlapping baffles or louvers which direct the flow of air through the baffles in an upward direction and which prevent the entrance of rain or snow, it being noticed that the cross sectional area of the air passages is only very slightly less than the entire area of the plurality of panels either in a compact or extended position.

Another object of the present invention is to provide a window ventilator that is constructed of a plurality of identically formed panels, each panel being provided with a series of baffles or louvers and the plurality of panels being secured together in a manner permitting lengthwise sliding movement relative to each other by readily detachable clips that engage the baffles or louvers.

With the above and other ends in view the invention consists in matters hereinafter set forth and more particularly pointed out in the appended claims, reference being had to the accompanying drawing, in which

Figure 1 is a front elevation of the present window ventilator;

Fig. 2 is a cross sectional view taken substantially along the line 2—2 of Fig. 1;

Fig. 3 is a transverse cross sectional view through one of the baffles;

Fig. 4 is a perspective view of the clip employed to secure the panels together;

Fig. 5 is a perspective view of one of the portions of the clip;

Fig. 6 is a perspective view of another portion of the clip, and

Fig. 7 is a perspective view of a modified form of clip.

Like characters of reference are employed throughout to designate corresponding parts.

The present ventilator comprises a pair of identical panels, each panel being formed with a rectangular marginal frame 1. To the frame 1 is secured a plurality of baffles 2 which are bent

throughout their entire length in the manner illustrated in Fig. 3. On the ends of each baffle are formed loops 3 adjacent the upper and lower edges of the baffles, the upper edge of the upper loop and the lower edge of the lower loop being cut on a bias as at 4. The loops 3 receive the wire 1 when the baffles are assembled and as illustrated in Fig. 1 the loops of one baffle rest against the loops of the next adjacent baffle and as a result of the loops being cut on a bias as described, the edge of any baffle overlaps the upper edge of the baffle arranged beneath a distance corresponding to the depth of the bias, this feature serving to prevent air from passing directly through the ventilator.

By arranging the baffles as described with the loops butting against each other, each baffle supports the next adjacent baffle in its proper position while the uppermost baffles and the lowermost baffles have their longitudinal edges bent around the adjacent portions of the wire frame 1 in the manner illustrated at 5.

To provide an adjustable window ventilator two or more of such panels are slidably secured together and for this purpose the present invention provides clips that engage the baffles in a manner to permit longitudinal sliding movement of the entire panels. In Fig. 4 such a clip is illustrated, this clip being formed of three separate parts that are sprung together, one of the parts being illustrated in Fig. 6 and which comprises a body having a vertically extending portion 6 with a horizontal portion 7 extending outwardly on one side from the top thereof and a horizontally extending portion 8 extending outwardly on the opposite side from the bottom thereof. Inclined members 9 are struck upwardly from the ends of the members 7 and 8 to extend alongside the body 6 in spaced relation thereto.

In Fig. 5 is illustrated the member that snaps on the above described body, there being one provided to snap on the members 9 on both portions 7 and 8, and this last mentioned member comprises a body 10 having springlike fingers 11 struck up on each end thereof, each spring finger being slightly hooked as at 12. A wall 13 extends outwardly adjacent the fingers on one side of the body and a flange 14 extends outwardly on the opposite side of the body 10 and spaced from the edges of the fingers 11.

In assembling two panels together by means of the present clip the body 6 is placed on the baffles of two panels that are placed side by side so that the upper edge of the baffle 15 engages

the portion 7 while the flat portion of the baffle engages the side of the body 6. The bottom edge of the adjacent baffle 16 on the opposite panel engages the portion 8 and the flat side of the 5 baffle lies against the opposite side of the body 6. The member 10 is then pushed downwardly on the clips 9 on the portion 8 so that the flange 14 extends outside the baffle 17, the upper edge of which engages the body 10 when the hooked 10 portions 12 have secured the body 10 to the body 6. Another body 10 is forced upwardly onto the members 9 on the portion 7 so that the flange 14 extends outside the baffle 18 and by repeating this 15 assembly adjacent each corner of the panels the latter are secured together in sliding relation.

In order to prevent the clips from sliding relative to the panels the baffles adjacent the clips, as illustrated in Fig. 1 may have prongs struck inwardly therefrom by cutting a portion of the 20 baffles as at 19.

In Fig. 7 is illustrated a modified form of clip which is formed of a single piece of metal having flanges 14' that engage baffles 17 and 18, and recesses or pockets 20 and 21 that receive the 25 baffles 16 and 15 respectively.

Although specific embodiments of the present invention have been illustrated and described it is to be understood that various changes may be made within the scope of the appended claims 30 without departing from the spirit of the invention, and such changes are contemplated.

What I claim is:

1. A ventilator comprising a plurality of panels, each panel comprising a marginal wire frame, a 35 plurality of baffles, loops formed on the ends of said baffles in a manner to receive said wire frame, and support said baffles so that the upper edge of one baffle overlaps the lower edge of the next adjacent baffle, and clips engaging certain of said 40 baffles for securing said panels together in a manner to permit sliding movement thereof relative to each other.

2. A ventilator comprising a plurality of panels, each panel comprising a marginal wire frame, a 45 plurality of baffles, loops formed in the ends of said baffles in a manner to receive said wire frame and support said baffles so that the upper edge of one baffle overlaps the lower edge of the next adjacent baffle, and lies in a plane spaced 50 therefrom, and clips engaging certain of said baffles for securing said panels together in a manner to permit sliding movement thereof relative to each other.

70

75

3. A ventilator comprising a plurality of panels, each panel comprising a rectangular wire frame, a plurality of baffles, loops formed on the ends of said baffles and bent around the ends of said wire frame and holding said baffles in parallel spaced relation with the lower edge of each baffle overlapping the next adjacent baffle, and clips slidably engaging said baffles in a manner to secure said panels together. 80

4. A window ventilator panel comprising a rectangular wire frame, a plurality of baffles, and a pair of spaced loops formed on each end of said baffles, said loops on each end being bent around the ends of said wire frame in opposite directions to support the upper edge of each baffle spaced from and overlapping the lower edge of the next adjacent baffle. 85

5. A window ventilator panel comprising a rectangular wire frame, a plurality of baffles, and a pair of spaced loops formed on each end of said baffles, said loops on each end being bent around the ends of said wire frame in opposite directions to support the upper edge of each baffle spaced from the lower edge of the next adjacent baffle, said loops being cut on a bias to support each 100 baffle with the lower edge thereof overlapping the upper edge of the next adjacent baffle. 95

6. A ventilator comprising a plurality of panels, each panel comprising a rectangular wire marginal frame, a plurality of baffles, a pair of spaced loops on each end of said baffles, said loops being bent around the ends of said wire frame in opposite directions and supporting said baffles with the upper edge of each baffle spaced from the lower edge of the next adjacent baffle, and clips 105 110 slidably engaging certain of said baffles in a manner to secure said panels together.

7. A ventilator comprising a plurality of panels, each panel comprising a rectangular wire marginal frame, a plurality of baffles, a pair of spaced 115 loops on each end of said baffles, said loops being bent around the ends of said wire frame in opposite directions and supporting said baffles with the upper edge of one baffle spaced from the lower edge of the next adjacent baffle; said loops 120 being cut on a bias whereby they support each baffle with the lower edge thereof overlapping the edge of the next adjacent baffle, and clips 125 slidably engaging certain of said baffles in a manner to secure said panels together. 125
